UNITED STATES PATENT OFFICE.

CLEMENT F. STREET, OF JOHNSTOWN, PENNSYLVANIA, ASSIGNOR TO THE
JOHNSON STEEL STREET RAIL COMPANY, OF KENTUCKY.

SWITCH-JOINT CHAIR FOR RAILWAYS.

SPECIFICATION forming part of Letters Patent No. 391,565, dated October 23, 1888.

Application filed May 24, 1887. Serial No. 239,184. (No model.)

To all whom it may concern:

Be it known that I, CLEMENT F. STREET, of Johnstown, in the county of Cambria and State of Pennsylvania, have invented a new and useful Switch-Joint Chair for Railways, which invention is fully set forth and illustrated in the following specification and accompanying drawings.

The object of this invention is to make a joint-chair for connecting switches and frogs to the main rails of the track, which connection shall be made by a single chair instead of two chairs at the divergent ends of the switch or frog.

15 The invention will first be described, and then particularly set forth in the claims.

In the accompanying drawings, Figure 1 shows in plan a side-bearing frog; Fig. 2, a center-bearing frog; Fig. 3, a part sectional end elevation of the joint-chair used in Fig. 1, looking from the left; Fig. 4, a part sectional end elevation of the chair used in Fig. 2, looking from the left. Fig. 5 shows the joint-chair in side elevation. Fig. 6 shows in plan a thrown-over switch. Fig. 7 shows in plan a blind switch. Fig. 8 is a part sectional end elevation of the joint-chair used in Fig. 7, looking to the left. Fig. 9 is a part sectional end elevation of the joint-chair used in Fig. 6, looking to the left. Fig. 10 shows Figs. 8 and 9 in side elevation.

In said figures the several parts are indicated by reference-letters, as follows:

A is the frog or switch-piece proper; B, the joint-chair, whose upper part fits with a splice-bar fit into the sides of the girder-rails of the switch. Should the webs of the rails be devoid of lower flanges, as shown by the rails *a* in Fig. 9, the part B of the joint-chair would 40 be preferably modified as shown in said figure.

A deep vertical web, C, unites the upper part of the joint-chair B to its base-plate *b b*, and said web is re-enforced by side webs or bases, *c c*. The bolts D are placed through holes *d* through 45 the upper part of the joint-chair B, and the outside plates, E, complete the fastening or joint by a splice-bar fit, if the shape of the rail permits, when set up in place by the bolts D, provided with threaded ends and nuts, as shown 50 in the drawings, for the purpose. If the shape

of the rails does not permit of a splice-bar fit, then plain plates E are set up by the bolts D, as seen in Fig. 9. These side plates, E, and the upper part of each joint-chair B are long enough to take in the two ends of adjoining 55 rails, and by means of such construction a supported joint is formed.

Practical experience has proved that in girder-rail constructions all joints should be properly supported. This is ordinarily done 60 by some usual form of supporting-chair at each joint; but the width of all ordinary chairs of good design is greater on the base than elsewhere, and consequently either the switch-piece must be so prolonged that its divergent 65 ends (under which is placed the chair) are so far apart as to permit the juxtaposition of two chairs, or else the ends of the switch-pieces must be staggered—that is, calling for alternate positions of two chairs. In either of said 70 cases the cost of the switch-piece is considerably increased, due to the addition to its length and weight; but such cost is obviated by the use of the joint-chair herein described, forming the subject of this invention. Said chair 75 possesses the further advantage of being so attached to the switch-piece as to be quickly and easily connected to the rest of the track. In the old method each of the two divergent ends of the switch-piece or frog had its own inde- 80 pendent joint and its own separate chair. This necessitated the insertion of one splice-bar and several bolts on the inside space between each of the rails, which space was very cramped and the joint consequently difficult to make or set 85 up. By the use of the joint-chair herein described the bolts and splice-bars or splice-plates are inserted and tightened up entirely from the outside, where room or space for work is unlimited.

Fig. 9 shows a cross-section taken through Fig. 6 at the line *x x*, looking to the left. G is the guard-rail, and *g* a chock, to which it is drawn hard up by setting up the nut of the bolt D. The head B of the chair also acts as 95 a chock, to which the rails are firmly secured by the bolt D.

The outside fish plates or bars are not a necessity; but their presence improves the structure.

Having thus fully described my said rail-joint chair as of my invention, I claim—

1. A joint-chair for the divergent meeting ends of switch or frog rails with the main-track rails, composed of an interior chock united to a lower base-plate by a central web and supporting said rails clear of the base, substantially as and for the purposes set forth.

2. A joint-chair for the divergent meeting ends of switch or frog rails with the main-track

rails, composed of an interior chock united to a lower base-plate by a central web and supporting said rails clear of the base, in combination with exterior splice bars or plates, substantially as and for the purposes set forth.

CLEMENT F. STREET.
